UNITED STATES PATENT OFFICE.

ERICH C. HEMPEL, OF EAST TAWAS, MICHIGAN.

DISHWASHING MACHINE.

Application filed March 20, 1923. Serial No. 626,281.

To all whom it may concern:

Be it known that I, ERICH C. HEMPEL, a citizen of the United States, residing at East Tawas, in the county of Iosco and State of Michigan, have invented certain new and useful Improvements in Dishwashing Machines, of which the following is a specification.

In carrying out the present invention it is my purpose to provide a dish washing machine whereby plates, cups and saucers may be washed simultaneously, and wherein subsequent to the washing of the dishes the water may be drained off and the dishes subjected to the action of draughts of air, so that the same may be dried.

It is also my purpose to provide a dish washing machine which will embrace the desired features of simplicity, efficiency and durability, which may be manufactured and marketed at small cost, which may be maintained and operated at a minimum expense, and which will embody comparatively few parts, and these so arranged and correlated as to reduce the possibility of derangement to a minimum.

With the above recited objects in view, and others of a similar nature, the invention resides in the construction, combination and arrangement of parts set forth in and falling within the scope of the appended claim.

In the accompanying drawings:

Figure 1 is a longitudinal sectional view through a dish washing machine constructed in accordance with my invention.

Figure 2 is a cross sectional view on the line 2—2 of Figure 1.

Figure 3 is a fragmentary sectional view through one of the cup holders.

Figures 4 and 5 are plan views of the cup holders.

Figure 6 is a perspective view of a saucer holder.

Referring now to the drawings in detail, 1 designates a substantially rectangular casing equipped adjacent to its lower wall with a false bottom 2 and provided in its top wall with a filling opening 3 closed by means of a cover 4. Mounted in the casing 1 above the false bottom 2 and spaced apart from such false bottom is a drum 5 that is circular in cross section. The end walls of the drum 5 are equipped with trunnions 6 that are journaled in the adjacent end walls of the casing 1 so that the drum 5 may be freely rotated within the casing. This drum 5 has its

side wall composed of foraminous material 7 and the foraminous material is provided with enlarged ingress openings that are closed by covers 8 that are also formed of foraminous material, these covers 8 being removable so that access may be had to the interior of the drum, in order to place the dishes therein in a manner to be presently described. The false bottom 2 is shaped after the fashion of a trough, as clearly shown in Figures 1 and 2 of the drawings, and the bottom wall thereof is inclined from one end toward the other and at its lower end communicates with an outlet cock 9, which may be opened in order to drain the water out of the trough after the dishes have been washed.

One of the trunnions 6 of the drum 5 is equipped with a beveled pinion 10 that meshes with a single pinion 11 on the upper end of a vertical shaft 12 that is journaled in suitable bearings 13 carried by the rear wall of the casing on the outer side of such wall. On the lower end of the shaft 12 is a beveled pinion 14 meshing with a similar pinion 15 fixed upon the armature shaft of an electric motor 16 that is fastened within the casing 1 to the bottom wall thereof below the false bottom 2. This motor 16 is under the control of an electric switch 17. Thus, when the motor 16 is energized, motion is transmitted through the beveled gears and the shaft 12 to the drum 5, so as to rotate the drum 5 within the casing 1.

At one end the drum 5 is provided with uprights 18, and spaced apart to define a rectangle and fixed to these uprights 18 at the bottom of the drum 5 is a wire plate rack 19, while slidably mounted upon the rods above the rack 19 is a rack 20 that cooperates with the rack 19, in order to hold the plates securely within the rack after such plates have been placed within the racks through the ingress opening in the drum. At its other end the bottom wall of the drum 5 on its inner side is provided with a cup rack 21 which is shown in detail in Figures 3, 4 and 5 of the drawings, and comprises, in the present instance, a bottom bar 22 fastened to the bottom wall of the drum. This bar 22 carries annuli 23 suitably fastened to the bar and spaced apart along the same. These annuli are of such diameter as to nicely receive the open ends of the cups. Above the bar 22 is a bar 24 parallel with the bar 22 and having its

ends slidably mounted upon posts 25 carried by the bar 22 adjacent to the ends thereof. This bar 24 may be locked in any position upon the post 25 by means of set screws 26. This bar 24 carries relatively small annuli 27 corresponding in position and number to the annuli 23, and these annuli 27 are of such diameter as to nicely receive the bottom ends of the cups, as clearly shown 10 in Figures 1 and 3 of the drawings. Thus, after the cups have been placed in the lower annuli the upper annuli carried by the bar 24 may be moved downwardly into engagement with the small ends of the cups, so as 15 to clamp the cups securely in position, the set screws 26 being manipulated for this purpose.

At the last mentioned end of the drum I also employ saucer holders which, in the 20 present instance, comprise vertical rods 28 secured in the drum 5 and spaced apart to define a rectangle. These rods 28 carry bars 29 which are two in number, and spaced apart in parallelism and the bars 29 are 25 slidable vertically on the rods 28. Below the bars 29 the rods 28 carry a saucer rack 30 which cooperate with the rods 29 to hold the saucers in position, as clearly shown in Figure 1 of the drawings. The bars 29 30 also carry spacer plates 31 adapted to be interposed between the saucers, as clearly shown in Figures 1 and 6 of the drawings, so that the saucers will be held spaced apart when placed within the rack.

When the drum 5 is at a state of rest and as shown in Figure 1 of the drawings, the motor 32 is energized by passing electric wires through the openings 35 and connecting the same with the socket which is electrically connected with the motor 32. During the time that the motor 32 is energized, the drum 5 remains stationary.

Mounted within the drum 5 centrally thereof is an electric motor 32 and fast to the 45 ends of the armature shaft of the motor 32 are fan blades 33 adapted to be rotated when the motor is energized to drive the air through the drum and over the dishes therein.

The rear wall of the casing 1 is equipped 50 with a housing 34 that encases the driving connections between the motor 16 and the drum and at its upper end this housing 34

is formed with a hand opening 35, by means of which the plug 37 may be inserted in and 55 removed from socket 36 carried by the adjacent end wall of the drum 5. Wiring 38 leads from the socket and is connected to the motor in any suitable way.

In practice, the dishes are placed within 60 the drum, as previously described, and the cover 4 removed so that the housing may be filled with water and soap or other cleansing solution for the dishes. The cover 4 is now replaced and the motor 16 energized, thereby revolving the drum 5 to thoroughly cleanse the dishes in the drum. After the drum has rotated for a sufficient period of time to cleanse the dishes, the motor 16 is shut off and the drain cock 9 70 opened, so that the water may drain out of the housing. The motor 32 is now energized so that the fan blades 33 will blow air over the dishes in order to dry the same and after the dishes have been dried the cover 75 sections 8 of the drum may be removed so that the dishes may be taken out of the drum through the opening 3.

While I have herein shown and described one preferred form of my invention by way 80 of illustration, I wish it to be understood that I do not limit or confine myself to the precise details of construction herein described and delineated, as modifications and variations may be made within the scope of 85 the claim and without departing from the spirit of my invention.

Having thus described the invention, what is claimed as new, is:—

A dish washing machine comprising a 90 casing provided at its end with an opening, a drum journaled in the casing for rotation upon a horizontally disposed axis, dish clamping means located interiorly of the drum, a motor located within the drum and having an electric connection communicating with the end of the drum and adapted to be disposed opposite the opening in the casing when the drum is at a state of rest, said motor having a horizontally disposed 95 shaft aligned with the axis of the drum and radially disposed blades carried by the motor.

In testimony whereof I affix my signature.

ERICH C. HEMPEL.
